UNITED STATES PATENT OFFICE.

RALPH A. CLAPPER, OF ALTOONA, PENNSYLVANIA.

DESIGN FOR AN INSULATOR.

46,862.

Specification for Design.

Patented Jan. 19, 1915.

Application filed January 13, 1914. Serial No. 811,928. Term of patent 7 years.

To all whom it may concern:

Be it known that I, RALPH A. CLAPPER, a citizen of the United States, residing at Altoona, in the county of Blair and State of Pennsylvania, have invented a new, original, and ornamental Design for Insulators, of which the following is a specification, reference being had to the accompanying drawing, forming part thereof.

The figure is a perspective view of an insulator, showing my new design.

I claim:

The ornamental design for an insulator, as shown.

RALPH A. CLAPPER.

Witnesses:

W. S. THOMPSON,
ADAM LEAKE.
